UNITED STATES PATENT OFFICE.

EDWARD C. WOOD, OF SOMERVILLE, MASSACHUSETTS, ASSIGNOR TO SUBMARINE SIGNAL COMPANY, OF WATERVILLE, MAINE, A CORPORATION OF MAINE.

SOUNDER ADAPTED FOR SUBMARINE USE.

1,189,028.

Specification of Letters Patent. Patented June 27, 1916.

Application filed February 12, 1912. Serial No. 677,263.

To all whom it may concern:

Be it known that I, EDWARD C. WOOD, of Somerville, in the county of Middlesex and State of Massachusetts, a citizen of the 5 United States, have invented a new and useful Improvement in Sounders Adapted for Submarine Use, of which the following is a specification.

My invention relates to sound producing 10 devices for use in submarine signaling, and particularly to pneumatically-actuated bells of a kind well known in the art.

The chief object of this invention is to provide an arrangement in which for every 15 impulse of fluid pressure admitted to the device a double blow will be struck on the bell.

According to this invention in its preferred form the bell hammer is connected to 20 two flexible diaphragms which are adapted to be actuated by fluid pressure under the control of a differential valve constructed in such manner that each impulse of fluid pressure upon the valve will move the valve 25 in one direction and cause air under pressure to operate a diaphragm to throw the clapper in one direction against the bell and when the impulse on the valve ceases so that the valve returns to its normal position the 30 other diaphragm will in like manner throw the clapper in the opposite direction, during which movement the air behind the first-mentioned diaphragm will be exhausted.

My present invention therefore relates to 35 a type of pneumatic bell in which the clapper is given a movement by two opposing diaphragms such that it will strike two opposite sides of the bell successively instead of one side only, this result being accomplished in the apparatus shown by a single 40 complete reciprocation of the valve.

As a matter of convenience of description I have described what is usually called the striker as comprising two parts, the 45 clapper which strikes the bell and the clapper arm which is the lever to which the clapper is attached and to which power is applied to cause the bell to be struck.

In this embodiment of my invention one 50 end of the clapper arm passes up into a casting and is there acted upon directly by two motors located opposite each other to push the end of the clapper arm first in one direction and then in the other, and the opening

in the casing through which the clapper arm 55 passes is closed by a flexible neck which, while flexible axially, is confined radially so that it will maintain a conical form under all ordinary conditions of pressure and use.

My invention will be understood by reference to the drawings in which its preferred embodiment is shown.

Figure 1 is a vertical section through the casing and bell, Fig. 2 being an enlarged vertical section taken at right angles to Fig. 65 1 and showing only the upper portion of the mechanism. Fig. 3 is an elevation of the portion of the mechanism shown in Fig. 2, the casing being shown in section. Fig. 4 is a section on line 4—4 of Fig. 2, and Fig. 5 70 70 is a plan showing the top of the casing.

A is the casing the lower end of which is closed by the plate A¹ and the upper end of which is provided with three openings, one a a pressure opening to carry compressed air to operate the motors, the second a¹ being an exhaust outlet, the third a² conveying impulses of compressed air to the valve as below described. The two compressed air inlets should be provided with some convenient form of pipe connection to connect them with a source of compressed air. A similar pipe will preferably lead from the exhaust opening 80 to above the water line. 85

To the under side of the plate A¹ is attached by means of suitable semi-circular cleats B¹ and bolts b the bell B, a rubber washer b¹ being located between the under-hang of the cleats and the flange b² of the 90 bell. The clapper arm C is hung on a shaft C¹ mounted in bearings C³ forming part of a cylinder or drum C². This drum C² has a circular opening in its lower end on opposite sides of which are the bearings C³, this 95 opening registering with the opening in the neck D which projects upward from the plate A¹ of which it is a part. A flange C⁴ on the drum C² is bolted to a corresponding flange on top of the neck D by bolts d. The 100 ends of the drum C² are closed by diaphragm holders F¹ and G¹ as below described. The top of the drum is also provided with an opening closed by the valve mechanism, the whole forming an exhaust 105 chamber A³ as described below. The upper end of the clapper arm carries a fork E¹ into which sets a block E² through which

passes a pin E^3 journaled in suitable bearings in a crossbar E . A neck C^5 conical in shape but open at the top and formed preferably of rubber or other elastic and flexible material is attached to the clapper arm C below the shaft C^1 by means of a clamp collar c of such character as to cause the neck C^4 to make a watertight joint with the clapper arm C . The lower end of this neck 5 turns outwardly and around the flange b^2 of the bell so as to act with the washer b^1 as a packing to prevent the leakage of water around the flange and up into the chamber A^3 as well as to provide proper acoustic insulation, the whole providing a perfectly flexible and yet watertight joint. The neck C^5 as shown has a number of wire rings c^1 molded in it which limit its radial expansion under pressure without limiting its 10 axial flexibility. A cloth insulation may be used instead.

The mechanism for reciprocating the crossbar E and thus causing the stroke of the bell comprises two diaphragms F and G , the centers of which are located approximately opposite each other, the two being so arranged and connected (as will be described below) that pressure will be applied to move one at the same time that all pressure upon the other is released, and the connection or crossbar E with the clapper arm C is such as to allow the upper end of the clapper arm to swing easily on its shaft. The ends of the crossbar E are threaded and 25 the connection of each end to its diaphragm is alike. These connections comprise two disks e , e^1 , each having a hole in the middle to enable it to be slipped onto the crossbar E . The disk e is first slipped upon a hub e^2 30 on the crossbar. The diaphragm F or G is then slipped on the crossbar, each diaphragm having a hole for the purpose. The disk e^1 which has a clearance hole is then slipped onto the end of the crossbar and 35 against the diaphragm, the whole being held in place by means of a nut e^3 which is screwed onto the end of the bar E and suitably locked.

The ends of the drum C^2 are as above 40 stated formed by annular diaphragm holders F^1 , G^1 , each forming a support for one of the diaphragms F , G , between which and the edge of the drum the edge of each diaphragm is clamped. To secure an air-tight joint between each diaphragm, its 45 holder and the drum each diaphragm holder is preferably grooved and the edges of the cylinder are provided with ribs or projections. Bolts f , g passing through the diaphragm holders and diaphragm force the diaphragms against the support and into the grooves, thus forming an airtight chamber between each diaphragm and its holder when the center of the holder is closed, the 50 whole also forming with the closure above

described an exhaust chamber A^3 within the cylinder.

The center of each holder is closed by means of a cup-shaped plug F^2 , G^2 containing preferably a resilient cushion F^3 , G^3 of 55 rubber or the like. Each plug is hexagonal or otherwise shaped so that it may be turned by a wrench and it is adjusted in place to give the crossbar E a slight rebound when it strikes the resilient material so that the 60 clapper after it has struck the bell will have a corresponding rebound and thus not deaden the vibrations of the bell.

The diaphragms F , G are set opposite each other. As is shown in Fig. 1 there is a space 65 or chamber F^4 between the diaphragm F and the holder F^1 whereas the diaphragm G and its support G^1 are in substantial contact. The clapper is caused to strike the opposite side of the bell from that shown in 70 that figure by reversing the positions of the diaphragms, the reversal being caused by delivering compressed air into the chamber G^4 between the diaphragm G and its holder G^1 and allowing the air in chamber 75 F^4 between diaphragm F and its holder F^1 to escape.

For the purpose of controlling and shifting the pressure from one diaphragm chamber to the other and so reciprocating the 80 clapper a differential valve H is provided located in a casting J , this valve controlling the pressure in two passages F^5 , G^5 , the one F^5 connected with the chamber between the diaphragm F and the holder F^1 , and the 85 other G^5 connected with the chamber between the diaphragm G and the holder G^1 .

The valve H is a differential reciprocating piston valve. It is moved downward by impulses of air delivered upon its upper surface, and is lifted upon the ceasing of each impulse by the air pressure in the pressure chamber A^2 which acts upon a fractional portion of its under surface, a valve rod H^1 being hollow for this purpose and being connected with the pressure chamber A^2 .

The valve H slides in a cylinder h located in the casting J . The casting is bolted by bolts j to a plate K . The plate K has three 95 passages, one k which connects the chamber j^1 in the casting J with the opening a^2 which conveys impulses of compressed air to the valve H , another a passage k^1 connecting the opening a^1 with the pressure chamber A^2 in the casing and third k^2 which 100 registers with the opening a and connects it with the passage L^1 . The joints between J , K and the inner wall of the casing A are 105 suitably packed to prevent leakage. The casting J has a long projection extending 110 down from its upper face and forming a closure to an opening in the top of the drum C^2 , closing this opening and preventing leakage between the pressure chamber A^2 and the exhaust chamber A^3 . This casting has 115

a shoulder j^2 against which the lower end of the cylinder h rests and it also has a sleeve j^3 having four series of perforations 1, 2, 3 and 4, which form at appropriate times air passages to allow the compressed air to pass to the chambers behind said diaphragms, or to escape therefrom as occasion may require. This sleeve also forms a bearing for the hollow valve rod H^1 of the valve 5 H. The bottom of the valve rod is of less diameter than the diameter of the top portion of the valve so that it offers a less area to air pressure below the valve than does the area of the upper surface of the valve. 10 Thus an impulse given through the opening a^2 at a certain pressure will drive the valve downward against a corresponding pressure on its under side applied through the lower end of the valve rod H^1 . The 15 valve rod is suitably packed and has by-passes h^2 and h^3 extending around it, these by-passes being of sufficient vertical length to connect two adjacent openings 1 and 2, 20 2 and 3 or 3 and 4.

25 In addition the casting J has ports 11, 12, 13 and 14 extending around it, which ports register with the openings 1, 2, 3 and 4, respectively, in the sleeve j^3 . The casting is also held in place by bolts j^4 against a suitable crossbar j^5 mounted on top of the drum C². As shown in Figs. 1 and 2 the valve is in its highest position, there being no pressure above it to counterbalance the pressure below it. The pressure below it is the pressure of the chamber A² which is communicated to the hollow chamber in the valve rod through the opening L and the passage L¹. 30 Upon the application of an impulse of compressed air through the opening a^2 which is connected with the source of compressed air above the water level by a suitable pipe, the valve H is depressed to its extreme lower position where it rests upon the top of the sleeve J³. The by-pass h^2 is thus 35 brought into position to connect the openings 1 and 2 and the by-pass h^3 is brought into position to connect the openings 3 and 4. As a result compressed air from the reservoir A² which is always under pressure of 40 say 30 pounds to the square inch, is communicated through the opening L and passage L¹ to port 11 through the openings 1, by-pass h^2 , openings 2, port 12, and to the passage L² leading to the opening G⁵ and 45 the chamber G⁴ where it acts on the diaphragm G inflating it and throwing the crossbar E and the upper end of the clapper arm C and causing the clapper to strike the bell. This same movement of the valve 50 brings the by-pass h^3 into position to connect the openings 3 and 4 and this allows the exhaust from the chamber F⁴ through the opening F⁵ in the diaphragm F and the passage L³, port 14, openings 4, by-pass h^3 , 55 openings 3 and port 13 into the passage L⁴, 60 L⁵, K² which connects the exhaust chamber A³ with the exhaust opening a leading out of the casing A preferably by a suitable pipe not shown. The exhaust passage L⁴ and chamber A³ are somewhat large so that the diaphragm chambers may exhaust freely. 65

When the impulse of compressed air on top of the valve H has ceased the parts resume the position shown in the drawings where the diaphragm chamber F⁴ is inflated, 70 the by-pass h^2 performing no function, compressed air passing from the chamber A² through the opening L and passage L¹ to the interior of the valve rod H¹ and out through the openings 4 and port 14 to the 75 passage L³ and opening F⁵ into the chamber F⁴. The chamber G⁴ is at the same time exhausted through the opening G⁶, passage L², port 12, openings 2, by-pass h^3 , openings 3, port 13 into the passage L⁴, L⁵, K² and out 80 through the opening a. This operation causes the crossbar E to be thrown across the casing thus throwing the clapper and causing it to strike the bell. It will be seen from Fig. 2 that the interior of the hollow piston rod H¹ will always be in communication with the pressure chamber A² even when the valve is in its lowest position and hence as soon as the impulse of compressed air is concluded and its force on top of the valve H 85 exhausted the valve will be lifted by the pressure under it.

In setting up the apparatus after the drum and other parts including the plate K and casting J are mounted on the plate A¹, 90 the casing A is bolted to the plate A¹, the parts being so proportioned that the casing may be clamped down on top of the plate K to form with rubber gaskets a watertight joint. 95

A⁴ is an eye by which the bell may be hung by a suitable shackle and chain. As the casing is usually made of bronze the shackle if of iron is best insulated from it by suitable washers, etc., of indurated fiber or the like. 105

The impulses to operate the valve H should be at the same pressure as that in the chamber A², the difference in effective areas of the under and upper sides of the valve being sufficient to insure its active operation. 110

By means of suitable code mechanism, which is now well known in this art, the impulses of compressed air from the source 120 of supply are controlled so that they may be delivered through the opening a^2 as desired so that the bell will be struck a double blow periodically or may be given any predetermined number of blows which may be 125 grouped or not as desired.

Although the differential valve above described is preferred for controlling the main diaphragms, it is not intended to limit the invention to its use as any other appro- 130

priate contrivance adapted to operate under the fluid pressure impulses may be employed for the purpose.

Other variations may be had from the mechanism shown and described above without departing from the spirit of my invention as set forth in the claims, for I do not mean in any case to limit my invention to the precise construction shown.

10. What I claim as my invention is:—

1. In a device of the character described, in combination, a casing having a sounder depending therefrom, a clapper arm mounted to swing, a cross bar pivotally connected to one end of the clapper arm, and a motor comprising a stationary part and a movable part, said movable part being attached to said cross bar whereby the movement of said movable part is imparted directly thereto, an adjustable resilient member located opposite said movable member and adapted to take the impact of the end of said cross bar opposite that attached to said movable member.

2. In a device of the kind described, a sounder, a clapper arm and a motor comprising a stationary part and a movable part, the two forming a chamber, said clapper arm having a cross bar attached to its upper end and said movable part being pivotally connected to one end of said cross bar to cause the clapper on said arm to strike the sounder, in combination with an adjustable resilient member located to be struck by the opposite end of said cross bar from that attached to said movable part substantially simultaneously with the striking of said sounder by said clapper, whereby said clapper will rebound after said sounder is struck and the extent of its rebound may be controlled.

3. In a device of the kind described, a sounder, a pivotally hung striker, means for operating said striker comprising two oppositely located members each connected to said striker and adapted to oscillate it to strike said sounder alternately at two opposite points, and resilient cushions located to receive an impact from said striker substantially simultaneously with the striking thereby of said sounder.

4. In a device of the character described, in combination, a sounder, a striker, a motor comprising a stationary part and a movable part, said parts forming a chamber, said stationary part having an opening therein, a closure for said opening adjustable therein and cushioning means located in said closure and adapted to receive the impact from said movable part, and means positively and directly connecting said striker with said movable part.

5. In a device of the character described, in combination, a sounder, a striker, a rigid diaphragm holder, a flexible diaphragm se-

cured at its edges to the edges of said holder, means operatively connecting said diaphragm and striker, said holder having a central opening and a plug closing the said opening and adjustable therein and carrying a resilient cushion located to receive the impact of said diaphragm.

6. In a device of the kind described, a watertight casing adapted to provide a reservoir for compressed air, a sounder depending therefrom, a motor located in said casing and adapted to be connected to said reservoir, and means for so connecting it, said motor comprising two oppositely located members, a clapper arm carrying a clapper at one end adapted to engage said sounder, its other end being located between and connected to both of said motor members, and bearings located within said casing, said clapper arm having means whereby it is supported to be oscillated on said bearings.

7. In a device of the kind described, a watertight casing providing a reservoir for compressed air, a sounder depending therefrom, a motor located in said casing and adapted to be connected to said reservoir, and means for so connecting it, said motor comprising two oppositely located members, means for connecting said members, a clapper arm carrying a clapper at one end adapted to engage said sounder, its other end being connected to the connection between said motors and pivotal means located in said watertight casing to support said clapper arm between its extremities.

8. In a device of the kind described, a watertight casing providing a reservoir for compressed air, a sounder depending therefrom, a motor located in said casing and adapted to be connected to said reservoir, and means for so connecting it, said motor comprising two oppositely located members, the space between said members comprising an exhaust chamber, means for connecting said members alternately with said exhaust chamber, means for connecting said members together, a clapper arm, one end being connected to said member connecting means, the other end carrying a clapper to engage said sounder, and flexible means connected to said clapper to close the lower end of said exhaust chamber.

9. In a device of the kind described, a watertight casing adapted to contain compressed air, a motor located in said casing, said motor comprising two oppositely-located connected parts, said parts being adapted to be operated alternately by compressed air, an exhaust chamber, connections to supply said parts alternately with compressed air and exhaust the pressure therefrom into said exhaust chamber, a sounder located outside said casing, a striker for said sounder, bearings for said striker located within said casing, and means within said

casing connecting said striker and said motor.

10. In a device of the kind described, a watertight casing adapted to contain compressed air, a motor located in said casing, said motor comprising two oppositely-located parts, said parts being adapted to be operated alternately by compressed air, an exhaust chamber, connections to supply said parts alternately with compressed air and exhaust the pressure therefrom into said exhaust chamber, a sounder located outside said casing, a striker for said sounder, bearings for said striker located within said casing, and means also located within said casing connecting the oppositely-located parts of said motor and pivotally connected to said striker whereby said striker will be moved in opposite directions to strike said sounder two successive blows on opposite sides thereof.

11. In a device of the kind described, in combination, a casing containing a pressure chamber, a sounder supported from said casing, a straight clapper arm pivotally supported in said casing to hang vertically therefrom, and carrying a clapper at its lower end within said sounder, a motor within said casing comprising a diaphragm arranged substantially parallel with the length of said clapper arm, and opposite the upper end thereof, and a cross bar connected to said clapper arm at right angles thereto and above its support and connecting said clapper arm with said diaphragm, whereby the movement of said diaphragm is exerted directly upon said cross bar and said clapper arm.

12. In a device of the kind described, in combination, a watertight casing, a bell located outside said casing, a clapper arm, one end of said clapper arm carrying a clapper and being located outside said casing, the other end of said clapper arm extending into said casing, a motor located in said casing and comprising a pair of diaphragm holders and oppositely-located diaphragms, one diaphragm being supported in each holder, said diaphragms being operatively connected with said clapper arm within said casing and adapted respectively to cause the clapper to strike said bell at opposite sides thereof.

13. In a device of the kind described, in combination, a watertight casing, a bell located outside said casing, a clapper arm, one end of said clapper arm carrying a clapper and being located outside said casing, the other end of said clapper arm extending into said casing, a motor located in said casing and comprising a pair of diaphragm holders and oppositely-located diaphragms, one diaphragm being supported in each holder, said diaphragms being operatively connected with said clapper arm within said

casing and adapted respectively to cause the striker to strike said bell at opposite sides thereof, said casing forming a chamber adapted to contain compressed air, and means for supplying air therefrom to operate said diaphragms alternately.

14. In a device of the character described, in combination, a bell, a single clapper within said bell, and operating mechanism for said clapper adapted to cause said clapper to strike said bell alternately at opposite sides, said operating mechanism comprising a casing having a pressure chamber, a motor comprising a pair of diaphragm holders and diaphragms, one diaphragm being connected to each diaphragm holder, said diaphragms being located opposite each other and forming diaphragm chambers, means connecting said diaphragms with said clapper and with each other, and means adapted to connect each diaphragm chamber alternately with said pressure chamber, said means comprising a reciprocating valve adapted with each reciprocation to connect one of said diaphragm chambers with said pressure chamber and allow pressure to exhaust from the other diaphragm chamber.

15. In a device of the character described, in combination, a casing, a pressure chamber contained therein, a bell, a clapper coöperating with said bell, and operating mechanism for said clapper adapted to cause said clapper to strike said bell alternately at opposite sides, said mechanism comprising a pair of diaphragm holders, a pair of diaphragms, each connected to one of said holders, said diaphragms being located opposite each other, means connecting said diaphragms with said clapper and with each other, and cushioning means located to receive the impact of said diaphragm-connecting means.

16. In a device of the character described, in combination, a bell, a clapper coöperating with said bell, and operating mechanism for said clapper adapted to cause the same to strike said bell alternately at opposite sides, said mechanism comprising a clapper arm and a pair of substantially parallel diaphragms arranged at opposite sides of said clapper arm and directly connected therewith.

17. In a device of the character described, in combination, a casing having a pressure chamber and an exhaust chamber, a bell carried thereby, a clapper coöperating with said bell, a pair of separate diaphragms operatively connected with said clapper and adapted respectively to cause said clapper to strike said bell at opposite sides, a pair of diaphragm holders each adapted to hold a diaphragm and form a diaphragm chamber therewith, an exhaust chamber located between said diaphragms connectible with

- said diaphragm chambers, and a differential valve one side of which is connected with said pressure chamber adapted to connect said pressure chamber with one of said diaphragm chambers and the other diaphragm chamber with the exhaust chamber and thereafter to connect said exhausted diaphragm chamber with said pressure chamber and said expanded diaphragm chamber 5 with said exhausted chamber, and means for operating said differential valve.
18. In a device of the character described, in combination, a casing having a pressure chamber and an exhaust chamber, a bell 15 carried thereby, a clapper coöperating with said bell, a pair of separate motors comprising a pair of diaphragms operatively connected with said clapper and adapted respectively to cause said clapper to strike 20 said bell at opposite sides, a pair of diaphragm holders each adapted to hold a diaphragm and form a diaphragm chamber therewith, an exhaust chamber located between said diaphragms connectible with 25 said diaphragm chambers, and a valve adapted to connect said pressure chamber with one of said diaphragm chambers and the other diaphragm chamber with the exhaust chamber and thereafter to connect 30 said exhausted diaphragm chamber with said pressure chamber and said expanded diaphragm chamber with said exhausted chamber, and means for operating said valve.
- 35 19. In a device of the kind described, a drum having an opening at its top and bottom, diaphragms closing the ends thereof, a striker one end of which is located within said drum and means for closing the opening 40 through which said striker end passes into said drum, means for connecting said diaphragm and said end of said striker and a valve casing and valve closing the open-

ing in the top of said drum, passages controlled by said valve connecting with the 45 chamber within said drum whereby said chamber will serve as an exhaust chamber for said diaphragms and an exhaust passage leading from said chamber and means for supporting said diaphragms whereby 50 the application of pressure behind said diaphragms will cause them to be operated.

20. In a device of the kind described, a casing, two diaphragm holders, each carrying a diaphragm, each diaphragm and 55 diaphragm holder forming together a diaphragm chamber, all located within said casing, means for supplying compressed air to said diaphragm chambers alternately, said means comprising a pressure chamber 60 located in said casing, a valve and passages connecting said pressure chamber and said diaphragm chambers controlled by said valve whereby the movement of said valve in one direction will cause the delivery of 65 pressure to one diaphragm chamber and the exhaust from the second diaphragm chamber, and the movement of the valve in the other direction will cause the delivery of pressure to the second diaphragm chambers 70 and the exhaust from the first diaphragm chambers, in combination with a striker connected to said diaphragm chambers whereby the movement of the valve in either direction will cause an operation of the 75 striker, the connection between said striker and said diaphragm being within said casing, and a bell located outside of and supported from said casing, one end of said striker being located outside of said casing 80 and in operative relation to said bell.
